WITNESS:

UNITED STATES PATENT OFFICE.

HILMAR MICHAELSON, OF WAUKEGAN, ILLINOIS.

ROCKER ATTACHMENT.

Application filed August 18, 1924. Serial No. 732,855.

To all whom it may concern:

Be it known that I, HILMAR MICHAELSON, a citizen of the United States, residing at 722 Mott Ave., Waukegan, in the county of 5 Lake and State of Illinois, have invented new and useful Improvements in Rocker Attachments, of which the following is a specification.

This invention relates to new and useful 10 improvements in rocker attachments for chairs and more particularly to rocker attachments which are especially adapted for attachment to ordinary straight-leg chairs such as diningroom chairs and the like.

15 The main object of my invention is the provision of a rocker attachment for straight-leg chairs whereby a diningroom chair or similar article of furniture may be readily converted into a comfortable rocking 20 chair.

Another object of my invention is the provision of a rocker attachment which can be quickly and readily attached to the lower ends of the legs of straight-leg chairs or 25 readily detached therefrom whereby diningroom chairs or the like may be advantageously used for different purposes.

With the above and other objects in view, the invention consists in the novel features 30 of construction, the combination and arrangement of parts hereinafter more fully set forth, pointed out in the claims and shown in the accompanying drawings, in which:

35 Fig. 1 is a perspective view of a detachable rocker constructed in accordance with my invention,

Fig. 2 is a side elevation showing the same applied to the legs of a chair,

40 Fig. 3 is a detail longitudinal section of end of rocker showing the same attached to the leg of a chair,

Fig. 4 is a detail section on the line 4—4 of Fig. 2 and

45 Fig. 5 is a detail section on the line 5—5 of Fig. 3.

In carrying out my invention, I provide the rocker members which in the present instance include a body member 1 which is 50 curved in proportion for ordinary use and in the present instance the rockers are illustrated as preferably of a flat type. The forward end of each of the rockers is provided with a recess 2 and attached to the body of

the rocker in alignment with this recess is a 55 plate 3 which is detachably secured to the rocker member by means of screws 4 although various types of fastening means may be used.

The outer end of the plate 3 is notched as 60 at 5. said notch being arranged directly above the recess 2 and forms spaced arms 6 at each side of the recess. The front legs 7 of the chair are provided with detachable buttons 8 which are held in place by means 65 of screws 9, thus retaining the buttons 8 in position against the lower end of the legs 7.

The buttons 8 as illustrated are provided with an annular groove 10 adapted to receive the spaced arms 6 of the plate 3 and it will 70 be noted that by forming the recess 2 in the forward end of the rocker, the buttons 8 may be readily engaged with the arms 6 of the plate.

The body of the rocker 1 is longitudinally 75 grooved as at 11 at a point adjacent the central portion of the rocker and attached to the rear legs 12 of the chair are the U-shaped clips 13 having pointed ends 14 which are driven into the lower ends of the legs 12 and 80 the arcuate bcdy portion of the clips will be disposed within the groove 11 in the rocker for not only retaining the legs 12 against transverse movement with respect to the rockers but also limiting the longitudinal 85 movement of the legs upon the rocker so as to retain the buttons 8 into engagement with the arms 6 of the plate 3.

From this it will be apparent that the rocker members 1 may be readily and quickly 90 attached to the lower ends of the straight legs of a chair for converting an ordinary straight-leg chair into a rocking chair. These rockers may also be quickly and readily removed from the chair when it is desired 95 to use the same as a dining room chair or the like.

From the foregoing description taken in connection with the accompanying drawings, it will be apparent that I have provided an 100 extremely simple, useful and inexpensive device for readily converting straight-leg chairs into rocking chairs and the device may be quickly and readily attached or detached as desired.

105 While I have shown and described the preferred embodiment of my invention, it will be understood that various changes and

alterations may be made without departing from the spirit of the invention or the scope of the appended claim.

Having thus described my invention, what I claim is:

In combination with the legs of a chair, buttons carried by one of said legs having an annular groove, ¹⁰ U-shaped clips attached to the lower end of the other leg, of a rocker, recesses in its forward end and a longitudi-

nal groove intermediate its ends, a plate attached to the rocker and projecting over said recess, a notch formed in one end of the plate providing spaced arms above said recess and adapted to be fitted into the annular groove ¹⁵ of the button, said U-shaped clips fitting into the longitudinal groove for retaining the rocker against movement relative to the legs.

In testimony whereof I affix my signature.

HILMAR MICHAELSON.
